UNITED STATES PATENT OFFICE

ROBERT D. BANE, OF LOS ANGELES, CALIFORNIA

PUMPING UNIT

Application filed December 5, 1927. Serial No. 237,693.

This invention relates to a pumping unit or pump jack and discloses a number of improvements thereon. An object of this invention is to disclose a compact and improved pumping unit of novel construction.

Another object is to disclose a pumping unit which is balanced, is capable of hard and continuous usage without repairs, is substantially noiseless and may be adjusted for changes in speed of pumping.

Another object is to disclose a pumping unit containing a minimum number of working parts and in which the power is most effectively transmitted to the pump.

Other objects and functions of this invention will become apparent from the later more detailed description of one preferred form of my apparatus.

After a well, for example, an oil well has been drilled, the oil flows to the surface of its own volition for a short time but sooner or later it is necessary to pump oil out of the well. The method customarily used in pumping is to lower a plunger pump down

into the tubing by means of a string of sucker rods and then pump the oil out of the well by imparting a reciprocating motion to the string of rods and pump. My invention is directed to a pumping unit designed to operate a string of rods or cable and pump.

As the weight of a string of rods is considerable in a deep well, I provide a counter-weight or counter-balance to assist in raising the tools and oil. Furthermore, my invention contemplates the use of substantially direct drive, utilizing, if desired, an electric motor mounted upon the base of the pumping unit and operably connected therewith by a suitable means such as worm and wheel gears or

sprocket and chain. The use of the chain drive facilitates changes in the gear ratio and in the speed with which the well is pumped. Furthermore, the construction disclosed by me provides that the drive and gearing be housed and lubricated constantly all as more fully described later.

For purposes of illustration, reference will be made to the attached drawings which show one preferred form of construction of my invention. Minor mechanical details

have been omitted in these drawings as such details are known in the art and it is to be understood that various modifications and changes may be made in the construction, my invention embracing all structures coming within the scope of the claims.

In the drawings, Figure 1 shows a side elevation of a pumping unit, and Figure 2 shows an end elevation of the unit.

Referring to the drawings, the unit comprises a base 1 having pillars 2, 3 and 4 thereon. Said pillars may be unitary with the base or they may be suitably attached to the base. A motor 5 is mounted upon the base or a portion thereof and operably connected with a shaft 6 journaled in pillars 2 and 3 by means of sprockets 7 and 8 and a chain 9. If desired, a worm and wheel gears may be used to impart power to the shaft 6. A gear 10 mounted on shaft 6 engages a larger gear 11 mounted on a crank shaft 12 which is journaled in the pillars 2, 3 and 4. Gears 10 and 11 may be either spur gears or screw or helical gears such as herring bone gears.

The crank shaft 12 has two cranks positioned thereon, one near each end of the shaft. The crank 13 is preferably equipped with a detachable counter-weight or weights 14. The size of this counter-weight depends upon the weight of the sucker rods and tools in the well being pumped or upon the depth of the well. A second crank 15 is mounted near the other end of the crank shaft 12 and so positioned as to be directly opposed or practically so to the crank 13.

The pillar 4 has upwardly extending guides 16. These guides may be made of channel iron suitably braced and connected at the top by a member 17 and further supported by means of tie-rods 18 and turn buckle 19. A cross head 20 of any suitable construction is mounted within the guide members 16 so as to allow a vertical, free motion to the cross head within the guide members. Rollers 21 and 22 may be provided between the cross head and the guide members so as to take up the stress imposed upon the cross head in all directions and reduce friction losses. The cross head carries a horizontal member 23 extending out beyond the guide members 16.

in both directions. The vertical motion is imparted to the horizontal member 23 and to the cross head 20 by means of a link or connecting rod 24, journaled on the crank 15 and suitably connected, for example, as indicated, by a ball and socket means 25. The horizontal member 23 is adapted to receive and hold a polished rod grip or grips 26 so as to firmly retain the polished rod 27 which passes through a stuffing box 28 attached to the top of a casing and tubing of the well 29.

If desired, gears 10, 11 and sprocket 7 may be housed within a casing 30, said casing extending around the space between piers or pillars 2, 3 and 4 so that lubricant may be contained within the casing and lubrication of the gears and crank shaft bearings facilitated. Lubrication of other bearings and the cross head 20 within the guides 16 may be accomplished in any suitable manner, for example, by means of a small pump capable of forcing lubricant into the bearings and cross head from the reservoir formed by the casing or housing 30 and driven by suitable gearing from the motor 5.

In operation, the pumping unit above described or a mechanical modification thereof is preferably positioned adjacent to a well casing 29 so that the distance between the vertical center line of the cross head and the line of connection of the connecting rod is substantially equivalent to the distance between the vertical center line of the cross head and the vertical axis of the well to be pumped.

In some cases it may be desirable to position the pumping unit at some distance from the casing 29 so as not to interfere with the removal of rods and tools from the well and under these conditions the polished rod 27 or cable attached thereto is passed over a sheave located above the well, for example, in the derrick positioned above the well and then attached to the polished rod grip or other attachment mounted upon the horizontal member 23.

It is to be noted that power is imparted to the crank shaft 12 at a point between the cranks 13 and 15 as I have found that this arrangement produces the most desirable results. In operating this pumping unit the weight of the tools and rods within the well tubing allows the pump to drop to the bottom of its stroke and when said pump and rods are raised the counter-weight 14 mounted on crank 13 assists in pulling these rods from the well to the upper end of the stroke.

My invention, therefore, comprises a pumping unit having a base and pillars thereon, a vertical cross head guide, and a cross head slidably mounted within the guide and operated by means of a connecting rod and crank mounted upon a crank shaft, a second crank equipped with counter-weights being positioned near the other end of the crank

shaft, power being applied to the crank shaft at a point between the cranks.

I claim:

1. A pumping unit comprising a base, vertical pillars positioned on the base, a motor mounted upon said base and operatively connected with a shaft journaled in the pillars, a crank shaft journaled in the pillars, a crank positioned near each end of said crank shaft, and substantially opposed to each other, means for transmitting power from the shaft to the crank shaft at a point between said cranks, a counterweight mounted on one crank, a connecting rod journaled on the other crank and operatively connected with a horizontal member and vertical crosshead, said horizontal member and vertical crosshead being slidably mounted within vertical guide means attached to the base, means carried by the horizontal member adapted to actuate a pump connection and a housing substantially covering said crank shaft and power transmitting means.

2. A pumping unit comprising a base, vertical pillars positioned on the base, a pair of spaced channeled guides extending vertically from one of said pillars, a cross head between said guides and within said channels, rollers carried by said cross head adapted to contact with webs of said guide channels, rollers carried by said cross head adapted to contact with flanges of said channels, a counter-balanced crank shaft journaled in said pillars, a crank carried by said crank shaft, a pitman operably connecting said crank and cross head, and means carried by said cross head adapted to grip and actuate a pump connection.

3. A pumping unit comprising a base, vertical pillars positioned on the base, a crank shaft journaled in the pillars, a crank mounted near each end of said crank shaft thereon, a counterweight mounted on one crank, a pair of opposed channeled guides vertically extending from one of said pillars, a cross head between said guides and within said channels, a pitman connected to said cross head and other crank, rollers carried by said cross head adapted to contact with webs of said guide channels, rollers carried by said cross head adapted to contact with flanges of said channels, a transverse member connecting the upper ends of said channeled guides, stay means connecting said transverse member to one of said pillars, a horizontal member carried by said cross head and extending beyond said base, and means carried by the horizontal member adapted to actuate a pump connection.

Signed at Los Angeles, California, this 28th day of November, 1927.

ROBERT D. BANE.
